CLAIM

The ornamental design for a car stereo with a touch-sensitive screen, as shown and described.

DESCRIPTION

FIG. 1 is a front elevation view of a car stereo with a touch-sensitive screen that has the design.

FIG. 2 is a rear elevation view of the article seen in FIG. 1.

FIG. 3 is a top plan view of the article.

FIG. 4 is a left-side elevation view of the article.

FIG. 5 is a right-side elevation view of the article; and,

FIG. 6 is a front, top, and side view of the article.

The broken lines represent parts of the article that form no part of the claimed design.
